UNITED STATES PATENT OFFICE

THEOPHIUS O. DUCKWORTH, OF SALT LAKE CITY, UTAH

POWER PUMP-ROD LIFT

Application filed August 6, 1929. Serial No. 383,949.

This invention relates to a power lift for a pump rod in wells. One of its objects is to provide a power driven pump rod lifter that will abolish the long stroke beam lift now used on many pumps.

Another object of this invention is to provide a reciprocating vertical motion for a pump with which any length of stroke may be had without increasing the width of the housing thereof.

Another object of this invention is to provide a pump rod lift that will give the up and down movement to the pump rod in a very small space and use a small amount of power for the operation thereof.

With these and other objects in view the invention comprises certain novel features of construction as hereinafter fully described and claimed.

20 In the accompanying drawing forming a part of this specification and in which corresponding parts are denoted by like reference characters, is illustrated the preferred form of embodiment of the invention capable of carrying the same into practical operation, it being understood that the invention is not necessarily limited thereto, as various changes in shape, proportions and general assemblage of its parts may be resorted to 25 without departing from the principles of the invention or sacrificing any of its advantages, and the right is therefor reserved for making all changes and modifications which will fall within the scope of the invention 30 and claims made therefor.

Referring to the drawing;

Figure 1 is a front view of the invention showing it in an upper stroke.

Fig. 2 is a front view of the invention 40 showing it in a downward stroke.

Fig. 3 is a side view of the invention.

Fig. 4 is a view through line 4-4 Fig. 1, of housing and guides.

Fig. 5 is an enlarged view through line 45 5-5 Fig. 3 of the support only.

Fig. 6 is a side view of the clamp 6.

Fig. 7 is a view of applicant's operating mechanism as applied to a pump.

Fig. 8 is a side view of idler roller bearing 50 25.

The reference character A denotes covering for a well to which the invention is attached, B a pipe within the well which supports a pump valve casing C at its lower end. D denotes a pump lifting rod which 55 operates the valves within the casing C when the invention is operated. E denotes a discharge pipe, and F a pulley.

The invention comprises in combination with a pump a support 1 secured onto the covering of a well by bolts or other means. In the front of the support are notches 3 and 4 having roller bearings 5 therein over which horizontally placed rods 2 travel back and forth through the notches. The rods 2 and the roller bearings 5 are secured within the notches by a yoke 6 secured to the support 1 by bolts 8. The clamp being notched at 7 to allow it to be placed over the rod 2.

On each end of the rods 2 are placed springs 70 9 to receive the lateral jar of the rods 2.

Secured to each end of the horizontal rods 2 are vertical guides 10 over which housing 11 moves up and down. The guides are secured to the rods 2 by a pin 12 passing through the guides and each end of the rods 2. The housing 11 having projections 13 on each side thereof. Each projection having a cleat 14 secured thereto by screws 15 in such a manner to hold the housing onto the guides 75 80 and to allow it to move freely up and down on the guides.

On the inner face of the housing 11 and in the center thereof is secured an endless rack 16 which is secured thereon by set screws 17. 85 To the bottom of the housing is pivotally connected a rod 18 which connects the housing with cross head 19 of the pump rod D. The cross head 19 travels on guide 20 on the support 1 and on guide 21 secured to the cover A 90 of the well.

Passing through a bearing 22 in the support 1 is a shaft 23 one end thereof being secured to pulley F and the other end thereof having a gear 24 attached thereto within the housing 11. Placed over the shaft 23 is an idler roller bearing 25 which is located between the bearing 22 and the gear 24 to hold the gears in mesh and upon which the outer rim of the casing travels, thus preventing the 95 100

wear on the inner face of the rim 27 of the housing as it is moved up and down or from side to side by the gear 25 when in operation. The roller bearing 25 also prevents an excess of lost motion as well.

5 In the operation of the invention the housing 11 moves upward, then sidewise, then downward and then sidewise to starting point, thus giving a pumping movement on 10 connecting rod 18 to rise and lower the pump rod D to draw liquid from the well.

Power is supplied to the invention by a belt over pulley F which is driven in the usual manner by engine or motor.

15 Having thus described the invention what I claim as new and desire to secure by Letters Patent, is:

1. In a power pump-rod lift comprising a support having notches therein, horizontally 20 moving rods within said notches, said rods having other rods secured to their ends thereof, said other rods forming guides, a housing having projections thereon, said projections for holding said housing on said guides in 25 such a manner that said housing can be moved upward and downward and means for operating said housing on said guides, all substantially as described.

2. In a power pump-rod lift comprising 30 an upright support having notches therein through which horizontally placed rods move back and forth, other rods secured to the ends of said horizontally placed rods, said other rods forming guides upon which a housing 35 operates up and down, said housing having projections thereon extending in such a manner to hold said housing onto said guides, said housing having an endless rack therein operated by a pinion secured to a shaft passing 40 through said upright, said rack and pinion to operate said housing, and means for connecting said housing to a pump-rod all substantially as described.

THEOPHIUS O. DUCKWORTH.
